UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

GAS RANGE.

Application filed March 26, 1922. Serial No. 627,832.

To all whom it may concern:

Be it known that I, GEORGE E. PICKUP, a citizen of the United States, residing at Newark, in the county of Licking and State 5 of Ohio, have invented a certain new and useful Gas Range, of which the following is a specification.

The invention pertains to a gas range of the type comprising an open top section 10 and an oven section. The primary object of the invention is to provide improved means for mounting the burner or burners in the oven section.

It has heretofore been the practice in the 15 manufacture of gas ranges of the type to which my invention relates, to mount the oven burners in the walls of the oven section in such a manner as to permit of a front-to-rear movement thereof for purposes of disconnecting the burners from the manifold along the front of the open top section. To 20 permit of such front-to-rear movement of the burners, it is necessary to provide enlarged openings in one side wall of the oven, 25 and special means must be provided for securing the burner or burners in place in the enlarged openings and to close the portions of the openings not filled by the burners.

30 The object of my invention more specifically stated is to provide a mounting for the oven burner or burners which will permit of the easy removal of the burner and at the same time reduce the cost of manufacture of the range.

An incidental aim of the invention is to utilize the burners as stays preventing the side walls of the oven section from warping under changes in temperature, producing a 40 disagreeable noise as well as resulting in an injury thereto.

In the accompanying drawings I have illustrated a preferred embodiment of the invention, but it is contemplated that various 45 changes may be made by those skilled in the art, in the form, construction and arrangement of the parts without departing from the spirit and scope of the invention as expressed in the appended claims.

50 Figure 1 of the drawings is a front elevational view of a gas range constructed in accordance with my invention. Fig. 2 is a fragmentary vertical sectional view taken approximately in the plane of line 2-2 of 55 Fig. 4. Fig. 3 is a fragmentary vertical

sectional view taken in the plane of line 3-3 of Fig. 4. Fig. 4 is a fragmentary plan view. Fig. 5 is a horizontal sectional view through the inner side wall of the oven section and showing a portion of a burner 60 mounted therein. Fig. 6 is an enlarged detail view showing the connection between the burners and the outer side wall of the oven.

The stove comprises generally an oven 65 top section 7 including a top frame 8 in which is adapted to be supported the usual grids (not shown). 9 indicates the oven section having upper and lower compartments located respectively above and below 70 the plane of the open top section. In the upper portion of the lower compartment is mounted one or more burners which serve both compartments. In the present instance I have shown two separate burners 75 10 and 11 passing through the inner side wall 12 of the oven section at a point slightly below the plane of the open top section and extending thence forwardly substantially at right angles for connection with a gas manifold 13 extending along the front of the open top section. The forward ends of the burners 10 and 11 are provided with the usual mixing bowls 14 into which discharge 80 the nozzles 15 of a pair of gas cocks 16 carried by the manifold. Similar cocks 17 control the flow of gas from the manifold to the burners (not shown) of the open top section in a manner well known.

85 The manifold 13 is carried by the top frame 8 of the open top section by means of a pair of brackets 18, and the arrangement is such that the end of the manifold farthest from the oven section is connected by means of a pipe 19 with the source of gas supply.

90 The inner side wall 12 of the oven section is suitably apertured to permit the burners 10 and 11 to pass therethrough as above set forth. Thus referring to Figs. 2, 5 and 6, 100 I provide apertures 20 in the side wall 12, of a diameter approximately equal to the diameter of the burners so that the latter fit relatively snugly in the apertures. The opposite or outer ends of the burners 10 and 11 are conveniently supported by a bracket 21 secured upon the inner side of the outer side wall 12^a of the oven section. To this end each of the burners is provided upon its outer end with a flat hook member 22 adapt- 105

ed to enter a slot 23 in the upper edge of the bracket 21. At opposite sides of the notch 23, projecting inwardly from the bracket, are one or more lugs 24 adapted to engage 5 with the shoulders 25 formed at the extreme end of the burner at the juncture of the hook member 22. It will be apparent that when the end of the burner is seated in the notch 23, it is incapable of longitudinal 10 movement in either direction.

Adjacent the apertures 20 in the side wall 12 near the opposite or inner ends of the burners, I provide upon each of the burners a projection in the form of a radially extending stud 26 which is adapted to engage 15 with the inner side of the wall 12 so as to hold the burner from moving relative thereto and at the same time holding the wall from bulging inwardly when expanded under the action of heat. It will be apparent 20 that the burners thus serve as stays to reinforce the oven section, preventing the side walls from warping and thus producing a disagreeable noise.

25 Each of the apertures 20, as shown most clearly in Fig. 3, is enlarged in one or more points as at 27 so as to pass the projections formed by the hook members 22, the stud 26, and a plurality of lugs 28. The latter 30 extend radially from the burners and serve to position properly upon the burners a lighter manifold 29. Normally, the enlargements 27 are located out of the way of said projections so that it is necessary before removing the burners to turn them to carry the respective projections into alignment with the enlarged portions 27 of the apertures. Preferably the edges of the apertures 20 are rounded or beaded as shown 35 clearly in Fig. 5, so as to facilitate the operation of sliding the burners through the inner side wall in assembling or disassembling the parts.

40 The forward ends of the burners are, as above mentioned, detachably connected with the gas cocks 16 on the front manifold 13 through the nozzles 15 entering the mixing bowls 14 of the burners. When it is desired to remove the burners from the oven section 45 I simply disengage the manifold from the bracket 18 adjacent the free end of the manifold and swing the latter outwardly sufficient to disengage the nozzles of the gas cocks from the mixing bowls. This outwardly swinging movement of the free end 50 of the manifold is so slight that the movement is taken up in the piping without in any way injuring or breaking the joints. To permit of the disengagement of the manifold 55 from the bracket 18 the latter preferably comprises a main or lower portion 30 secured at one end to the underside of the top frame 8 by means of a bolt 31 and having at its opposite end a socket portion 32 60 in which the manifold is arranged to rest.

A cap member 33 is then secured upon the lower or main member 30 as by means of a bolt 34. The side edges of the member 30 are flanged downwardly so as to lend strength to the bracket and the same is true 70 of the cap member 33. In practice it is only necessary to remove the bolt 34 and the cap member 33, and loosen the bolt 31 slightly, to permit of the disengagement of the manifold from the bracket.

75 It will be apparent that the method herein disclosed of supporting the oven section is exceedingly simple. A single operation forms the apertures through which the burners pass, and the studs 26 coating with the edges of these apertures normally to hold the burners against relative movement therein, are preferably cast integral with the burners. Consequently, the usually required plates or supporting brackets for supporting the burners in this wall of the oven section are eliminated. Furthermore, the burners may be readily removed when desired by simply disconnecting the manifold therefrom in the manner set forth.

90 I claim as my invention:

1. A gas range having, in combination, an open top section and an oven section having its inner wall adjacent the open top section and having an aperture therein near the plane of the open top section, a burner for the oven section including a substantially straight main portion adapted to be inserted into the oven through said aperture and to fit snugly therein so as to be held against lateral movement in the aperture, the outer side wall of the oven section having a part rigid therewith with which the opposite or free end of said burner portion is detachably connected, said burner also including a portion extending forwardly from the main portion upon the outside of the oven but beneath the open top section, and a gas manifold extending along the front of the open top section and having a detachable connection with said burner, said manifold being adapted to be swung outwardly away from the open top section whereby to disengage it from the burner.

110 2. In a gas range having an open top section and an oven section, an oven burner, a gas manifold with which said oven burner has a detachable connection, one wall of the oven section having a hole therein of a size substantially equal to the diameter of the burner and through which the burner is arranged to pass, and a projection on the burner adapted to engage with the edge of the aperture so as normally to prevent longitudinal movement of the burner, said aperture having an enlargement with respect to which said projection is normally offset but adapted to receive the projection to permit of the movement of the burner in the aperture.

3. A gas range having an oven with opposed side walls, a burner for the oven, means upon one of said side walls for supporting one end of the burner, the opposite 5 side wall having an aperture therein adapted snugly to receive the burner and having an enlargement, said burner having a projection normally offset with respect to said enlargement to engage the side wall at the 10 edge of the aperture to prevent an inward bulging of said side wall.

4. In a gas range, an oven having opposed

side walls and a burner, said burner being mounted at one end so as to contact with one of said opposed side walls at the inner side 15 thereof and adapted to engage with the other one of said walls whereby the burner is supported in position in the oven and serves as a stay to prevent the side walls from bulging inwardly. 20

In testimony whereof, I have hereunto affixed my signature.

GEORGE E. PICKUP.
